UNITED STATES PATENT OFFICE.

GEORGE W. PRESCOTT, OF HIGHLAND, CALIFORNIA.

BURNER FOR PULVERIZED COAL.

SPECIFICATION forming part of Letters Patent No. 606,239, dated June 28, 1898.

Application filed December 14, 1896. Serial No. 615,573. (No model.)

To all whom it may concern:

Be it known that I, GEORGE W. PRESCOTT, a citizen of the United States, residing at Highland, San Bernardino county, California, 5 have invented certain new and useful Improvements in Burners for Pulverized Coal, of which the following is a specification.

My invention relates particularly to that class of burners that are used for the burning of coal that has been reduced to a pulverulent or comminuted condition, and especially to mechanisms for forcing the comminuted fuel into the fuel-chamber of either a locomotive or stationary boiler.

15 The object of my invention is to provide a simple, economical, and efficient burner adapted for the introduction of comminuted coal into a furnace; and the invention consists in the features, combinations, and details of construction hereinafter described and claimed.

In the accompanying drawings, Figure 1 is a side elevation, partly in section, of a portion of a locomotive engine and cab fitted 25 with my improvements; Fig. 2, a longitudinal sectional elevation of a locomotive-tender adapted for use in connection with my improvements, taken on the line 2 of Fig. 3; Fig. 3, a transverse section through the tender, taken on the line 3 of Fig. 2; Fig. 4, an enlarged sectional elevation of a portion of a locomotive, showing my improvements in operative position, taken on the line 4 of Fig. 5; Fig. 5, a plan view of a portion of the 35 mechanism, looking at it from line 5 of Fig. 4; Fig. 6, a plan view of a cam for shaking the burner; Figs. 7, 8, and 9, sectional elevations of the mechanism, taken on lines 7, 8, and 9, respectively, of Fig. 4; Fig. 10, an enlarged sectional elevation of a portion of the 40 mechanism, taken on line 10 of Fig. 5; and Fig. 11, an end view of a portion of the valve-operating mechanism, looking at it from the line 11 of Fig. 4.

45 In the art to which this invention relates it is well known that there is a certain grade of bituminous coal in the western and southwestern parts of the United States known as a light bituminous or "lignite" coal. The 50 specific gravity of this coal is so light that during the ordinary process of burning or combustion portions of it in the shape of

large sparks and incandescent cinders are apt to leave the locomotive and set fire to the property adjacent to the railway-tracks, thus 55 causing considerable loss to property and oftentimes endangering human life. My invention is intended, primarily, to obviate this objection by providing mechanism in which this coal may be burned after it has been reduced to a pulverized or finely-divided condition. By my improvements when the coal has been reduced to this finely-divided condition it may be burned without causing any 60 sparks or smoke, not only resulting in the 65 safety of property, but in the economy of fuel.

In describing and illustrating my improvements I prefer to describe and illustrate them in connection with a locomotive-engine as showing one of the purposes to which they 70 are applicable. It will be understood, however, that they are applicable to all kinds of furnaces, either for the generation of steam or for producing energy in many of its different forms. Further, in describing my improvements in connection with a locomotive-engine I will only describe that portion which I consider to be new, taken in connection with so much of the mechanisms as are old as to properly disclose my invention and enable 75 those skilled in the art to practice the same, leaving out of consideration the other and old mechanisms, which are well known and which would only tend to confuse or render the specification and claims ambiguous. 85

In constructing a locomotive and providing it with my improvements I provide a locomotive A of any of the general and well-known types having a fire-box or fuel-chamber A'. At the lower portion of the rear wall of the 90 fire-box I arrange my burner B, which is constructed as follows: I provide a casing B', preferably rectangular in shape when looked at in plan view, and preferably having its fuel-passage b arranged on a downward incline. The upper portion of the burner is provided with a pivoted valve gate or door B² and of a width of the fuel-passage, which forms the upper wall of the passage and which is movable transversely across the passage. This door is provided with a handle and lever mechanism b', that extends up into the cab of the locomotive, whereby the valve-door may be raised or depressed, so as to con- 95 100

trol the size of the burning exit-opening b^2 , which regulates, as it were, the amount of fuel fed direct to the furnace.

The fuel-passage is connected to the tender by means of a flexible pipe C, which has a ball-joint or socket c where it connects with the burner and a substantially ball-joint and telescopic socket c' where it connects with the tubular pipe C', that leads from the tender. 5 Intermediate of these two is what might be termed a "knuckle-joint" c², thus providing a flexible pipe, as it were, between the burner and the tender, so that the engine and tender are enabled to take the curves properly 10 and not interfere with the passage of fuel from the tender to the burner.

I provide a tender D the platform and trucks of which may be constructed in any convenient manner and the fuel-reservoir of which 20 is constructed to form a substantially hopper-shaped receptacle d, having flaring side portions and bottom portions, the forward end of which is provided with a tube or pipe C', that connects with the delivery or burner tube. The cover d' of the hopper is provided 25 with doors d², through which the coal may be inserted into the hopper-chamber.

To feed the fuel directly into the fire-box in the desired manner and assist materially 30 in the completing of the combustion, I provide the burner with a lower portion E, having a passage e for fluid-pressure through the same. The exit-opening e² of this fluid-pressure passage is arranged underneath in line 35 with and adjacent to the burning exit-opening of the fluid-passage, so that as the fuel flows over or out of the fuel-passage it is met directly by the outgoing blast of steam or air and forced into the furnace, so that 40 both of these openings—opening b² and the opening e²—form the burning exit-openings of the burner—that is, the fuel can be ignited at these points—and by having these burning exit-openings and arranged on the exterior 45 of the burner the feeding and burning of the fuel can be better controlled. This passage is connected by means of a pipe E' with a steam-head e', arranged in any convenient location on the locomotive, so that steam under 50 pressure may be delivered to the burner at a point where the comminuted coal leaves the burner, acting thereby to force the coal in its divided condition into the chamber under pressure, thus enabling the gases in the 55 coal to be readily and quickly distilled, take up the proper quantity of atmospheric air and be readily ignited before smoke can be formed, as well as to be readily consumed, either in the shape of olefiant gas or carbonaceous material, thus preventing sparks of any size from forming and passing out of the stack of the locomotive. To regulate the 60 amount of fluid-pressure for the burner, I provide a slide-valve E², and preferably arrange it in the exit-opening of the pressure-chamber, so that its movements backward and forward open the exit-opening to the

desired extent or completely close the same. This valve is provided with worm-and-gear mechanism e² at the rear portion thereof, 70 which has a vertical rod E³ extending up into the cab of the locomotive, by which the mechanism may be operated and controlled.

It is desirable to keep the fuel in the delivery-tube in an agitated condition, so that 75 it will more readily feed into the burner, and in order to accomplish this result I provide the driving-wheel axle G with a cam g and pivotally mount a flexible agitating-rod G' on the strap g', located preferably under the 80 deck of the cab. One end of this agitating-rod, as at g², is connected with the fuel-delivery tube and the other end provided with a pin g³, that enters a groove in the cam G. It will thus be seen that as the locomotive 85 is running a vibratory action is imparted through the rod to the delivery-tube, agitating the material therein and causing a more efficient feed of the material to the burner. This agitating-rod, for convenience, is made 90 flexible or in two parts, pivoted together at g⁴ and provided with a spring g⁵, that tends to keep its pin in engagement with the cam. In order to force it out of engagement with the cam when desirable, I provide a rod G², 95 that extends up into the cab of the locomotive and connects its lower end by means of a pivotal lever g⁶ and link g⁷ with the agitating-rod, so that the free end of such agitating rod may be depressed by pulling the rod 100 G² upwardly. The upper portion of the rod is provided with a pin and pin-holes g⁸, so that it may be held in such manner as to keep the agitating-rod in or out of engagement with the cam, as desired.

It is often desirable in first starting the operation of the parts to facilitate the passage of the fuel through the delivery-tube, and in order to accomplish this result I provide one portion of the delivery-tube with a fluid-pressure injector H, which is connected by means of a pipe h with a source of steam-supply. It is only necessary to use this injector at the beginning of combustion or at any time when the tube should become clogged, so as to either 110 facilitate the passage of the fuel therethrough or clean it out, as desired.

While I have described my invention with more or less minuteness as regard details as being embodied in certain precise forms and adapted to certain specific structures, I do not desire to be understood as limiting myself thereto unduly or any more than is pointed out in the claims. On the contrary, I contemplate all proper changes in form, construction, and arrangement, the omission of immaterial elements, and the substitution of equivalents as circumstances may suggest or necessity render expedient.

I claim—

1. A burner for comminuted fuel provided with a longitudinal fuel-passage therethrough and an independent passage for fluid-pressure having its exit-opening arranged underneath

130

135

140

in line with and adjacent to the burning exit-opening of the fuel-passage in the burner, so as to feed the fuel direct to the furnace, and a valve-gate in the fuel-passage movable 5 transversely of the passage to govern the passage of fuel therethrough, substantially as described.

2. A burner for comminuted fuel provided with a longitudinal fuel-passage and an independent passage for fluid under pressure having the exit-opening of the pressure-passage arranged adjacent to, in line with, and underneath the burning exit-opening of the fuel-passage so as to feed the fuel direct to the 10 furnace, a pivoted valve gate or door forming the upper wall of the fuel-passage and movable transversely of the fuel-passage to control the flow of fuel therethrough, and a valve in the exit-opening of the pressure-passage, substantially as described.

3. In mechanisms of the class described the combination of a burner for comminuted fuel provided with a longitudinal fuel-passage and a passage for fuel under pressure having 25 the exit-opening of the pressure-passage arranged adjacent to and underneath the exit-opening of the fuel-passage, a pivoted valve gate or door forming the upper wall of the fuel-passage and movable transversely of the 30 fuel-passage to control the flow of fuel therethrough, a valve in the exit-opening of the pressure-passage, and a flexible pipe connecting the fuel-passage of the burner with a supply-reservoir, substantially as described.

35 4. In mechanisms of the class described the combination of a burner for comminuted fuel provided with a longitudinal fuel-passage and a passage for fluid under pressure having the exit-opening of the pressure-passage arranged 40 adjacent to and underneath the exit-opening of the fuel-passage, a pivoted valve gate or door forming the upper wall of the fuel-passage and movable transversely of the fuel-passage to control the flow of fuel therethrough, 45 a valve in the exit-opening of the pressure-passage, a flexible delivery-pipe connecting the fuel-passage of the burner with a source of fuel-supply, and means for agitating such delivery-pipe, substantially as described.

50 5. In mechanisms of the class described, the combination of a burner provided with a longitudinal fuel-passage therethrough and a fluid-pressure passage with its exit-opening arranged adjacent to and underneath the exit-opening of the fuel-passage, a gate in such fuel-passage movable transversely in such passage, means connecting such gate with mechanism in the cab of the locomotive, a tender 55 provided with a hopper-shaped receptacle for the reception of fuel in a comminuted condition, a flexible delivery-tube connecting the fuel-passage of the burner with the fuel-receptacle of the tender, a cam arranged on a movable part of the locomotive and means connecting the cam with the delivery-pipe so

as to agitate the same during the movement of the locomotive, substantially as described.

6. In mechanisms of the class described, the combination of a burner provided with a longitudinal fuel-passage therethrough and a fluid-pressure passage with its exit-opening arranged adjacent to and underneath the exit-opening of the fuel-passage, a valve-gate in such fuel-passage movable transversely in 70 such passage, means connecting such gate with mechanism in the cab of the locomotive to open and close the same, a tender provided with a hopper-shaped receptacle for the reception of fuel in a comminuted condition, a flexible delivery-tube connecting the fuel-passage of the burner with the fuel-receptacle of the tender, a cam arranged on a movable part of the locomotive, a flexible rod connecting the cam with the delivery-tube to agitate 75 the same during the movement of the locomotive, and means for throwing the rod into and out of engagement with the cam, substantially as described.

7. In mechanisms of the class described, the combination of a burner provided with a longitudinal fuel-passage therethrough and a fluid-pressure passage with its exit-opening arranged adjacent to and underneath the exit-opening of the fuel-passage, a valve-gate in 90 such fuel-passage movable transversely in such passage, means connecting such gate with mechanism in the cab of the locomotive to operate the same, a tender provided with a hopper-shaped receptacle for the reception 95 of fuel in a comminuted condition, a flexible delivery-tube connecting the fuel-passage of the burner with the fuel-receptacle of the tender, a cam arranged on a movable part of the locomotive, means connecting the cam 100 with the delivery-pipe so as to agitate the same during the movement of the locomotive, and a fluid-pressure injector arranged in the delivery-tube to assist in the passage of fuel therethrough and clean such delivery-tube, 105 substantially as described.

8. In mechanisms of the class described, the combination of a burner for comminuted fuel provided with a longitudinal fuel-passage and a fluid-pressure passage with its exit-opening 110 arranged adjacent to and underneath the exit-opening of the fuel-passage, means connecting the fluid-pressure passage with a source of fluid-pressure supply, a pivotal gate movably arranged transversely in the fuel-passage and forming an upper wall thereof, a valve in the exit-opening of the pressure-chamber, rod-and-lever mechanism connecting the gate of the fuel-passage with a handle in the locomotive-cab, mechanism arranged in the locomotive-cab connected with the valve in the pressure-chamber for operating the same, a tender provided with a hopper-shaped receptacle for holding fuel in a pulverized or comminuted condition, a flexible tube connecting the fuel-passage of the burner with the hopper-shaped receptacle, a 115 120 125 130

cam on the drive-wheel axle of the locomotive, a flexible rod pivotally mounted on the locomotive connected with the flexible tube and arranged to be engaged with the cam on the driving-wheel axle to agitate the flexible tube, mechanism arranged in the locomotive-cab and connected with the flexible agitating-

rod to hold the same in or out of engagement with the cam, substantially as described.

GEORGE W. PRESCOTT.
